UNITED STATES PATENT OFFICE.

AQUILA MOORE, OF NEW HAVEN, CONNECTICUT, ASSIGNOR TO PECK BROS.
& COMPANY, OF SAME PLACE.

WASTE-PLUG FOR WASH-BASINS.

SPECIFICATION forming part of Letters Patent No. 392,819, dated November 13, 1888.

Application filed September 24, 1888. Serial No. 236,188. (No model.)

To all whom it may concern:

Be it known that I, AQUILA MOORE, of New Haven, in the county of New Haven and State of Connecticut, have invented a new Improvement in Waste-Plugs for Wash-Basins; and I do hereby declare the following, when taken in connection with accompanying drawings and the letters of reference marked thereon, to be a full, clear, and exact description of the same, 10 and which said drawings constitute part of this specification, and represent, in—

Figure 1, a side view, a portion of the head-flange broken away to show the supporting-stud; Fig. 2, a vertical central section; Fig. 3, 15 a side view of the socket-sleeve, showing the vertical slot therein; Fig. 4, a transverse section through the tube above the sleeve H.

This invention relates to an improvement in that class of stoppers for wash-basins which 20 are arranged outside the basin proper and supported in the top independent of the basin, and so that the upper end, projecting above the top, serves as a handle by which to withdraw or introduce the plug, and which device may 25 also serve as the overflow for the basin, the object of the invention being a simple, cheap, and effective device; and the invention consists in the construction, as hereinafter described, and particularly recited in the claim.

30 A represents a socket constructed at its upper end with a flange, B, to rest on the top of the wash-stand, and is provided with a screw-threaded flanged nut, C, below, by which it may be firmly clamped to the top. Through this 35 socket the plug-tube D is arranged. This tube is of external diameter corresponding to the diameter of the socket B, and at its lower end is provided with a plug, E, of suitable material, such as india-rubber. This plug is hollow and 40 made so as to open into the tube D, the plug itself being adapted to enter and fill the waste F, this waste being applied in the usual manner.

The tube D extends above the socket A and terminates in a closed head, G. The socket is 45 extended above the flange B, so as to form an annular sleeve, H, around the tube D above the socket, but through which the tube D may slide freely up and down. The head G is constructed with a downwardly-projecting con-

centric flange, I, of larger internal diameter 50 than the external diameter of the sleeve H, and so that as the said tube is raised up and depressed the said flange I of the head will accordingly slide up and down upon the sleeve H. The sleeve H is constructed with one or more 55 vertical slots, a. (See Figs. 3 and 4.)

Diametrically through the tube D a bar, b, is introduced, which projects upon opposite sides, forming studs d, corresponding to the vertical slots a in the sleeve H. These studs 60 stand above the lower edge of the flange I of the head and in such relation to the sleeve H that when the studs rest on the top of the sleeve H the said flange I will still overlap the said sleeve, as seen in Fig. 2. When the sleeve 65 is turned to bring the said studs into line with the slots a, then the tube D will drop, as indicated in broken lines, Figs. 1 and 2, so as to bring the plug E into its seat, and so as to close the waste, the studs passing down in the slots 70 a. Then to open the waste, the tube D is raised to take the studs d out of the slots and above the end of the sleeve H. Then a partial rotation given to the tube D will bring the studs onto the upper edge of the sleeve and into 75 notches e, formed therein, as seen in Fig. 1, where the tube will rest. The notches, however, may be dispensed with and the studs simply rest upon the upper edge of the sleeve H.

The head G of the tube serves as a convenient handle by which it may be raised, and the flange I practically covers the mechanism between the tube and its socket, whereby it is permitted to be raised and held in the raised position or dropped into the closed position, 85 thus giving a neat and finished appearance to the head, but yet hiding the mechanism of the device.

In case the tube D is to be used in the overflow, as in many cases is done, the tube is perforated at the required height, as at f, Figs. 1 and 2—a common expedient in this class of 90 plugs.

While this plug is made with special reference to wash-basins, it will be understood that 95 it may be used in connection with bath-tubs and for other purposes where such a plug is applicable.

From the foregoing it will be understood that I do not claim, broadly, a tube arranged within a socket, carrying a plug at its lower end and provided with a head at its upper end, by 5 which the said tube may be raised or dropped, and with mechanism between said tube and socket, whereby the said tube may be supported in the open position, as such, broadly considered, I am aware is not new.

10 I claim—

The combination of the stationary socket A, constructed with a concentric sleeve, II, upon its upper end, the tube D, movably arranged through said sleeve and socket, the said tube 15 provided with a plug at its lower end adapted

to close the waste and at its upper end constructed with a head closing the said upper end, and the said head constructed with a downwardly-projecting concentric flange, the internal diameter of which corresponds substantially to the external diameter of the said sleeve on the socket and so as to inclose the same, the said sleeve constructed with one or more vertical slots and the tube provided with corresponding studs, substantially as and for 25 the purpose described.

AQUILA MOORE.
